UNITED STATES PATENT OFFICE.

WILLIAM CLELAND LEONHARD, OF PASSAIC, JOHN ROY DUFFORD, OF PATERSON, AND ARTHUR HOUGH, OF SUMMIT, NEW JERSEY.

PROCESS FOR BLEACHING SULPHURIC ACID.

No Drawing.

Application filed January 18, 1924. Serial No. 687,123.

To all whom it may concern:

Be it known that we, (1) WILLIAM CLELAND LEONHARD, (2) JOHN ROY DUFFORD, and (3) ARTHUR HOUGH, citizens of the United States of America, residing at (1) Passaic, (2) Paterson, and (3) Summit, in the counties of (1 and 2) Passaic and (3) Union, and State of New Jersey, have invented certain new and useful Improvements in Processes for Bleaching Sulphuric Acid, of which the following is a specification.

The present invention relates to the process of bleaching sulphuric acid, particularly sulphuric acid containing substantial amounts of organic matter, by means of electrolysis.

The process is applicable to the treatment of acid containing organic matter whether this is in the form of carbo-hydrates, more or less decomposed carbo-hydrates, pure carbon, hydro-carbons, or other similar materials, and will be particularly described with relation to the treatment of sulphuric acid which has been used for parchmentizing paper. The process stated, broadly consists in the decomposition of water in the presence of sulphuric acid and a manganese salt and organic matter as above described.

The manganese sulphate has been found to be most satisfactory but other manganese salts or compounds can be used, such as the chlorid nitrate, carbonate, etc., which compounds would be converted into the sulphate during the process. The quantity of manganese sulphate necessary to produce best results may vary within certain limits and may be as low as .25 of 1% or as high as 2% of the sulphuric acid undergoing treatment. Larger quantities e. g. 2% can be used. It has been found that $\frac{1}{2}$ of 1% of the manganese sulphate gives very good results with a consumption of electrical energy well within economical operating limits. The manganese sulphate is not reduced in quantity only to the extent of that lost mechanically by factory operations such as the amount of sulphuric acid lost during the process of washing the parchment paper.

It has been found that the nascent oxygen evolved at the surface of the anode in the cell acts on the manganese sulphate producing permanganic acid. This permanganic acid reacts on the organic matter and as an ultimate product we have manganese sulphate reproduced quantitatively. By

this means, the organic matter present in the sulphuric acid is oxidized with production of CO_2 and without any loss whatever of the original quantity of manganese salt employed with the exception of such losses as may result from factory operations above referred to.

To carry out this invention and for the production of best results, it is preferable to have the sulphuric acid of a strength not below 40% H_2SO_4 and not higher than 70% H_2SO_4 . The temperature of this acid should be in the neighborhood of 80 to 100° centigrade, if lead peroxide anodes are used. If platinum, gold, or other materials, such as magnetite, are used for the anodes, then the temperature of the acid must be in the neighborhood of 130° centigrade. It is preferable to use electrodes with a ratio of anode surface to cathode surface, four to one. The current density best suited for this work has been found to be about one-fifth of an ampere per square inch of anode surface, although this current density may be varied within wide limits and with good results. The end point is reached when the acid assumes a slight pink color which is an indication that practically all the organic matter has been oxidized. On standing a short time this pink color disappears and the acid is bleached. It has been found that the best material for the anodes is electrolytic peroxide of lead and, by this, we refer to the hydrated peroxide of lead resulting from the electrolytic oxidation on a lower oxide such as the protoxide or litharge, PbO as it is commonly termed.

As the particular form and method of construction of this type of anode forms the subject matter of a separate invention it will not be described in this specification but this patent is understood to cover the use of electrolytic peroxide of lead in connection with this new and improved bleaching process.

We claim:

1. A process of bleaching sulphuric acid containing organic matter which comprises the step of passing a current of electricity through such sulphuric acid containing a small percentage of manganese compound in solution.

2. A process of bleaching sulphuric acid containing organic matter in the form of carbon in suspension which comprises the steps of adding a small proportion of man-

- ganese sulphate and passing through the acid an electric current until such organic matter has been substantially removed.
3. A process of bleaching sulphuric acid containing organic matter in the form of a hydro-carbon which comprises passing an electric current through the acid containing manganese compound.
4. A process of bleaching sulphuric acid containing organic matter in the form of a hydro-carbon which comprises passing an electric current through the acid containing a small percentage of manganese sulphate.
5. A process of bleaching sulphuric acid containing a carbo-hydrate which comprises passing an electric current through the acid containing manganese sulphate.
6. A process of bleaching sulphuric acid containing organic compound which comprises passing an electric current through the sulphuric acid containing a manganese salt employing anodes consisting largely of electrolytically prepared peroxide of lead.
7. A process of bleaching sulphuric acid containing organic matter by passing an electric current through the acid containing a manganese salt and employing electrodes,
- the anodes having a larger surface than the cathodes.
8. A process of bleaching sulphuric acid containing organic matter by passing an electric current through the acid containing manganese sulphate and employing electrodes, the anodes having a larger surface than the cathodes.
9. A process of bleaching sulphuric acid containing organic matter which comprises passing a current of electricity through the acid containing a manganese salt using electrodes of any suitable material.
10. A process of bleaching sulphuric acid containing organic matter which comprises passing a current of electricity through the acid containing manganese sulphate using electrodes of any suitable material.

In testimony whereof we affix our signatures in presence of two witnesses.

WILLIAM CLELAND LEONHARD.
JOHN ROY DUFFORD.
ARTHUR HOUGH.
